UNITED STATES PATENT OFFICE.

PATRICK B. DELANY, OF SOUTH ORANGE, NEW JERSEY.

TELEPHONY.

1,194,280.

Specification of Letters Patent. Patented Aug. 8, 1916.

Application filed June 5, 1911. Serial No. 631,494.

To all whom it may concern:

Be it known that I, PATRICK B. DELANY, a citizen of the United States of America, residing at South Orange, county of Essex, 5 State of New Jersey, and at Nantucket, county of Nantucket, State of Massachusetts, have invented a certain new and useful Improvement in Telephony, of which the following is a specification.

10 My invention relates especially to dictation by telephone requiring the spoken words to be recorded or transcribed by the person receiving the message.

The introduction of letter telegraphy has 15 brought telephone dictation into extensive use for collection of messages at the telegraph office from subscribers. This improvement is not connected with transmission or articulation at the receiver, but is 20 designed for the betterment of the service as a whole and affords the speaker perfect guidance in the matter of speed so as to keep the dictation within the recording ability of the receiving operator, the speaker being 25 able to follow the recordation of each word and regulate the rate of speaking accordingly. For this purpose my invention comprises novel means for transmission back to the sending station of the vibrations, dis- 30 turbances, jars, scrapings, gratings, or other effects produced by the pen, pencil, stylus, typewriter or other recorder of the message, whereby the speaker at the sending station hears distinctly the recording of 35 each word dictated and in this way can immediately follow one sentence or phrase with another without danger of speaking too fast and with perfect assurance that all the words have been recorded by the receiving 40 operator. The return transmission automatically effected, is a perfect guide. The speaker also knows whether the last word is understood by the receiver, for if not he does 45 not hear the record making he consequently repeats the word without any request from the receiver. In fact the insight of the person transmitting into the operation at the receiving end is almost equivalent to actual seeing of what is being done. Crossing of a 50 "t" and dotting of an "i" as well as punctuation are easily recognized and each word on account of its length and the long or short strokes of the letters may, practically, be followed letter by letter when recorded 55 by pen or pencil. In this way confusion arising from vocal acknowledgments and

delay due to the receiving operator waiting are avoided.

Although my invention broadly covers apparatus for sending to the transmitting station any automatically effected progressive acknowledgment of recordation, I show in the drawings only a few specific ways of accomplishing the results referred to, all being, however, based upon the same general 60 principles.

In the accompanying drawings: Figures 1 to 13 inclusive have detailed somewhat dia- 65 grammatic drawings indicating various modifications.

Referring to Figs. 1 and 2, 1 indicates an ordinary desk telephone, 2 a transcribing board having a circular notch on one side and an arm 3 secured to the board, just inside the notch, and that extends laterally and 70 is formed with a hook at its end. The relation of the parts is shown in Fig. 1. The hook embraces the standard of the telephone and the board lies upon the curved telephone base.

75 In Fig. 3, 4 indicates an ordinary microphone mounted on a transcribing board 2. The microphone is included in a local bat- 80 tery circuit 5 containing the primary coil 6 of an induction coil, the secondary 7 of 85 which is in the telephone circuit.

Fig. 4 shows substantially the same ar- 85 rangement except that the microphone 4 is mounted on the under face of the board.

Fig. 5 shows a transcribing board with a 90 circular notch 8 at one side and short feet 9 at the other side. The board is to be pushed up against the standard of a desk telephone so that the notched end will be supported 95 upon the base of the telephone and the oppo- site end will rest upon the feet 9.

Fig. 6 shows a transcribing board having 95 three upwardly projecting pins 10.

In Fig. 8 which shows the bottom of the base of a desk telephone, 11 indicates the 100 ordinary felt covering on the bottom and 12 indicates three openings through the felt so that the metal base of the telephone may rest directly upon the pins 10.

In Fig. 7 a telephone stand is shown 105 standing on the pin 10.

In Fig. 9, a transcribing board is provided at one end with a two-jawed clamp adapted to spring over and embrace the standard of a desk telephone. At the opposite end the 110 board is provided with feet 9.

In Fig. 10, the board has secured to it a

spring metal clamp 13 under which may be pushed the base of of a desk telephone.

Fig. 11 indicates diagrammatically the keyboard part 14 of a typewriting machine having projecting laterally on one side, a spring arm 15 under which the base of a desk telephone may be pushed.

Fig. 12 shows diagrammatically the key board part of a typewriter carrying a stand 10 and 16 on which is suspended an ordinary microphone.

Fig. 13 shows an ordinary desk telephone suspended from a fixed bracket hook 17 so that its base will be out of contact with the 15 transcribing board 2. The telephone may be readily disengaged from the hook by the operator and placed upon the sounding board. In this case it is preferable that there shall be no felt covering on the bottom 20 of the telephone base.

All the figures of the drawing represent various devices located at the reception end where received messages are transcribed either by pen, pencil or stylus on the transcribing board or by means of a typewriting machine; and in either or all cases, the sender of the message is apprised of the progress of its recordation. Of course, when the receiving operator has recorded what he 25 has received, he may tap on the sheet lying on the transmitting board to indicate to the sender that he is ready for more. When the recordation is done by means of a typewriter, the operator may transmit some 30

characteristic signal to the sender to indicate that he is ready,—as for instance there might be a special key or device on the typewriting machine that would operate for instance a mechanical buzzer.

I claim:

1. The combination with a main telephone line of a transmitter for the sending station, a receiver at the receiving station, a transcribing board at the receiving station, a microphone mounted thereon and secured thereto, and a battery circuit for said microphone connected with the main telephone line.

2. The combination with a main telephone line, of a transmitter for the sending station, a receiver at the receiving station, a transmitter at the receiving station, a transcribing device at the receiving station insulated from extraneous sounds and mechanically connected with the transmitter at the receiving station whereby messages received from the sending station may be transcribed at the receiving station and telephonic impulses corresponding in general characteristics with the impulses received from the sending station may be sent back over the line to the sending station.

In testimony whereof, I have hereunto subscribed my name.

PATRICK B. DELANY.
